UNITED STATES PATENT OFFICE

160,560

EXPANSIBLE WATCH BAND OR SIMILAR
ARTICLE

Tobias Stern, Scarsdale, N. Y., assignor to Jacques Kreisler Manufacturing Corporation, North Bergen, N. J., a corporation of New Jersey

Application January 7, 1950, Serial No. 7,058

Term of patent 7 years

(Cl. D45—4)

To all whom it may concern:

Be it known that I, Tobias Stern, a citizen of the United States, residing at Scarsdale, in the county of Westchester and State of New York, have invented a new, original, and ornamental Design for an Expansible Watch Band or Similar Article, of which the following is a specification, reference being had to the accompanying drawing, forming part thereof.

In the drawing

Fig. 1 is a front elevational view of an expansible watch band embodying my new design with the conventional end links shown in broken lines, the links shown in full lines being continuous throughout the length of the band as indicated by the broken lines across the center;

Fig. 2 is a rear elevation of the band as shown in Fig. 1;

Fig. 3 is a top edge view of the band as shown in Fig. 1; and

Fig. 4 is a front elevational view thereof illustrating the links in an expanded position.

I claim:

The ornamental design for an expansible watch band or similar article, substantially as shown.

TOBIAS STERN.
